UNITED STATES PATENT OFFICE

2,655,199

LOUNGE CHAIR

Frank J. Luketa, Seattle, Wash.

Application February 7, 1950, Serial No. 142,825

6 Claims. (Cl. 155—105)

1

This invention concerns a lounge chair which, in common with my other applications herein-after identified, has two main body-supporting members, a seat and a back respectively, each tiltably supported for movement independently of the other, their common tilting axis being located in the vicinity of the upper rear edge of the seat, and which chair also has two auxiliary body-supporting members, a head rest and a leg rest respectively, each supported for tilting, the head rest relative to the swinging edge of the back and the leg rest relative to the swinging edge of the seat, and one or both of which may be projected and retracted relative to its main body-supporting member. Reversible power means permits or effects each such movement of each such member independently of any other movement, the controls to such ends being located conveniently to the chair's occupant.

The present chair in many respects resembles that disclosed in my abandoned application Serial No. 723,171, filed January 20, 1947. Therein the seat and the back are tilttable about a common axis, defined by coaxial but unconnected trunnions projecting outwardly from the two sides thereof. The power being applied at one side for tilting the seat, and at the other side for tilting the back, it is necessary to equalize the application of such power in order to avoid sagging of the opposite side, wherefore such power was transmitted from side to side by a countershaft offset from the tilting axis, and connected at its two ends to the two corresponding trunnions. In contrast to the construction of that abandoned application, the present construction simplifies and condenses the countershaft construction, and connects it more directly, hence more rigidly and strongly, to the trunnions.

It is desirable that no gap of variable width be left between the adjoining edges of the seat and back, for there is the possibility that a lessening gap might pinch the chair's occupant. It is, in part, to avoid this possibility, while at the same time avoiding a rigid cross connection at this juncture of the edges, which in itself would be uncomfortable, that the trunnion mount is used, with no connection across at this point. A similar construction is disclosed in my copending application Serial No. 103,987, filed July 11, 1949, now Patent No. 2,629,428, but therein duplicate tilting drives are provided, connecting the power means directly to each side of the seat and the back. This complicates the power take-off and the drive connections, and increases the cost of the whole. In the present construction, involving a single tilting drive and a cross connection,

2

there is a simplification of the drive connection, and certain structural modifications to obtain like results with the changed drive mechanism.

In connection with the leg rest in particular, which is projectable as well as tilttable, if it is depressed while it is extended, or even if the seat whereon it is pivotally supported be depressed under like conditions, the leg rest may contact the floor, and damage may result to the mechanism unless under such circumstances the power may be disconnected at once and automatically. My Case O discloses means to that end, and herein is disclosed other and simplified means to the same end, which is likewise helpful in the assembly and disassembly of the chair, and which can be applied equally well to the head rest and its support.

The leg rest, and preferably also the headrest, is projectable and retractable in addition to being tilttable, being supported on telescopingly interengaged elements constituting supporting arms. While the particular mechanism for accomplishing projection and retraction is not herein disclosed, mechanism to such end is disclosed in my Patent 2,629,428 or in my copending applications Serial No. 98,511, filed June 11, 1949, or Serial No. 127,218, filed November 14, 1949, and any such mechanism may be employed herein for such purpose.

The motive power for movement of the several members can be supplied by an electric motor and selected, reversely operable power take-offs, such as are shown in my application Serial No. 98,511 in particular, or in Patent 2,629,428.

The present invention, then, comprises an arrangement of the several elements, each old in itself, in a novel and simplified way, to the ends already indicated. Further objects and advantages will appear hereinafter.

In the accompanying drawings the invention is shown embodied in a typical form, such as is presently preferred by me.

Figure 1 is a general plan view of the chair, the seat and back being each shown in section, the planes of their sections meeting at the common tilting axis.

Figure 2 is a general side elevational view, with the side arms in section along the line 2—2 of Figure 1.

Figure 3 is a view similar to Figure 2, but showing parts in section along the line 3—3 of Figure 1.

Figure 4 is in general a vertical axial sectional view along the line of the common tilting axis of the seat and back, the line being shown generally at 4—4 in Figure 1.

Figure 5 is a view similar to Figure 3, omitting the back, however, and illustrating in particular a safety provision operable in the event of undue depression of the leg rest while it is extended.

Figure 6 is a detail isometric view of the support elements for the leg rest, disconnected in the same manner as in Figure 5.

Figure 7 is a detail view of the jackscrew for supporting and tilting the leg rest, illustrating in particular the manner of its connection to the leg rest, such as will permit disconnection in the manner illustrated in Figures 5 and 6, the viewpoint being suggested by the line 7—7 of Figure 3.

The seat 1 and the back 2, each pivotally supported upon the floor-engaging frame 3, constitute the main body-supporting members. The leg rest 4 is in this instance pivotally supported from the seat 1, although upon an axis offset from the tilting axis of the seat, and the head rest 5 is likewise pivotally supported with respect to and upon the back 2, but also upon an axis offset from the tilting axis of the back. The tilting axis of the back and seat is an axis common to both of them, and preferably is located at the junction between the top surfaces of each thereof, that is to say, at the top rear edge of the seat and at the lower forward edge of the back, and these two main body-supporting members meet, without any substantial gap, along the line of their common tilting axis.

The leg rest and the head rest, constituting auxiliary body-supporting members, are, in addition to being tiltably supported, each projectable and retractable with respect to the swinging edge of the main body-supporting member with which they cooperate, respectively.

Each floor-engaging frame 3 is made up in general of forward and rearward floor-contacting elements, side elements connecting them in a generally rectangular tubular frame, and upright standards 39 which project through slots in and are disposed within hollow arms 29 which are secured at 28' (see Figure 2) to the back 2 to tilt with the latter.

The back 2 is pivotally mounted on hollow trunnions 20 which project outwardly from its opposite sides, and upon which, or formed as a part of which, are gear elements 21, principally directed downwardly. The seat 1 is similarly pivotally supported upon short trunnion elements 10, which project beyond the trunnions 20 outwardly from and are secured rigidly to the opposite sides of the seat 1. These have formed as part thereof or secured to them, gear members 11, which also project more or less downwardly. The two trunnions are mounted for oscillation in the standard 39, the hollow trunnions 20 surrounding and moving about a sleeve 30 which is part of the standard 39, and the inner trunnions 10 being journaled within the sleeve 30. Each of the trunnions is provided at its inner end with an attachment plate, such as that indicated at 27 in Figure 2, which attaches the trunnions 20 to the back 2 by the screws 28 or equivalent means. In similar fashion the trunnions 10 are secured to the seat.

Offset from the common axis of the trunnions 20 and 10, and preferably a short distance below the same, are two cross shafts, 12 and 22, respectively, the shaft 22 being hollow and formed for ready assembly in two interfitting parts, as indicated at 22a, these two coaxial countershafts or cross shafts being journaled in the standards 39. The shaft 22 carries a gear member 23, and the shaft 12 carries a gear member 13, which mesh with the respective gear elements 21 and 11. The

shafts 12 and 22 are located close enough to the common tilting axis that stresses are minimized, and yet sufficiently below the same that these concentric shafts 12, 22 will fit into the gap between the adjoining ends of the seat and back frames, and will never be contacted by the occupant of the chair. They will not interfere with the down-tilting of either of these main body supporting members, but instead the seat and the back may reach an approximately horizontal position if need be. Oscillation of the shaft 12 will effect oscillation of both trunnions 10 equally and of the seat 1, whereas oscillation of the shaft 22 will effect oscillation of the trunnions 20 equally and of the back 2.

Such oscillation is accomplished by connecting to the shaft 22 at one end a radial arm 24 (see Figure 1 at the bottom, and Figure 2) and by connecting to the shaft 12 a similar arm 14 (see Figure 1 at the top), and to these arms are connected jackscrew mechanisms which will shortly be described in greater detail, each of which is independently energizable. It will be observed that the tilting is initiated at one side only, but the stresses are equalized from side to side, and no sagging is permitted, because of the rigid and direct interconnection between the sides which is afforded through the cross shafts 12 and 22, respectively, and their direct gear connection at each side to the corresponding trunnions.

The leg rest is supported on telescopingly connected arms, of which the arm 41 is the innermost radially and the arm 42 slides therewithin. The arms 41 are connected across by a cross tube 43, which is tiltably mounted upon a supporting cross shaft 40 (see Figure 5), which is carried by a rearward extension of the frame of the seat 1, at a point offset rearwardly of and below the common pivot axis of the seat and back. Any suitable mechanism, such as is disclosed in copending applications referred to hereinabove, but which is not shown here in detail, may be employed for extending or retracting the arms 42 with respect to the arms 41, and the actuating means for so doing are indicated generally at 49. The tilting of the arms 41, 42 is accomplished by jackscrew mechanism, including the jackscrew 48 and the rotating means therefor at 48a, as will be explained shortly in greater detail. Each of the arms, that is to say those at the opposite sides, are driven in common but each by separate actuating means.

Each jackscrew 48 is swivelly mounted at 47 upon the frame of the seat 1, and threaded upon it is a nut 46, which carries externally a headed stud 46a. This stud is receivable within a downwardly opening notch 45a of a collar 45, which is carried upon the corresponding arms 41. Each nut is provided with laterally outstanding wings or fingers, 46b (see in particular Figure 6), which engage the frame of the seat 1 and prevent rotation of the nut in response to rotation of the jackscrew 48. Moreover, the end of the jackscrew distant from the swivel mount at 47 is confined within a slot 44 for limited swinging movement as the jackscrew swivels and the arms 41 swing in a plane parallel to the side frame of the seat. It will now be evident that so long as the head 46a is engaged within the notch 45a, the nut will support the leg rest and its arms 41 in any tilted position, and will raise or lower the same. However, when the downward movement, whether caused by downward movement of the nut 46 or by downward tilting of the supporting seat 1, proceeds to such a point as is indicated

in Figure 5, that the leg rest contacts the floor

F before the powered downward movement ceases, the nut 46 will merely withdraw its stud 46a downwardly from the notch 45a, and no harm will result. Whenever the nut 46 is run up again along its screw 48, the stud 46a will re-engage within the notch 45a, and thenceforward upward movement of the nut will raise the leg rest, as before. This provides a simple safety factor.

The head rest is similarly supported upon arm parts 51 and 52, similarly telescopingly interconnected and actuated by the drive element 59, and is similarly mounted upon the back by a tubular cross member 53 for tilting. In just the same fashion a screwjack 58, acted upon by a nut 56, serves to raise or lower the headrest with respect to the back. While there is less danger that downward movement of the headrest will encounter some immovable obstacle, nevertheless, interconnecting the nut 56 with the collar 55 in the same way as was described with respect to the leg rest, will serve as an ever-present safety factor, and the construction is further helpful in assembling or disassembling this part of the chair. Raising or lowering of the headrest is under control of the element 58a, which, like the element 48a, may be in the form of a flexible shaft, and each of the arm members 51, one at each side, is directly connected to the drive through such a flexible shaft 58a.

Tilting of the seat and of the back may be similarly effected through jackscrews 18 and 28, acted upon by the flexible shafts 18a and 28a, respectively, these jackscrews carrying the nuts 15 and 25, respectively, connected to the arms 14 and 24.

A single motor M may serve as the motive power for all such movements, under control of switches S carried upon the arms 29 in position convenient to an occupant of the chair. The motor may be supported in a convenient location, as, for instance, on the under side of the seat 1, and the power may be supplied selectively, to each of the mechanisms to be operated, through a selective power take-off illustrated at P. From the latter lead various flexible shafts through selective clutch mechanism to the power drives such as those at 18a, 28a, 48a, 49, 58a, and 59.

I claim as my invention:

1. A lounge chair comprising a floor-engaging frame, a main body-supporting member pivotally supported thereon for tilting, means so to tilt the same, an auxiliary body-supporting member disposed outwardly of the swinging edge of the main body-supporting member, arms on the outer

ends whereof said auxiliary body-supporting member is supported, said arms being pivotally mounted at their inner ends upon the main body-supporting member to tilt with as well as 5 relative to the latter, a jackscrew swivelly supported from the main body-supporting member, a nut non-rotatively engaged by the main body-supporting member, and threaded upon said jackscrew, a notched element and a headed element, one on the nut and the other on said arms outwardly of their pivot support, and interengageable by downward swinging of the auxiliary body-supporting member and its arms relative to the nut, and disengageable by upward swinging thereof, and means to rotate said jackscrew to raise and lower said arms when parts are so engaged.

2. A lounge chair as in claim 1, wherein the nut is formed with lateral projections, and is disposed close alongside an upright surface of the main body-supporting member, where the projections may engage such surface to prevent rotation of the nut.

3. A lounge chair as in claim 2, including further, means constraining the lower end of the jackscrew to movement in a plane parallel to the upright surface.

4. A lounge chair as in claim 1, wherein the arms are formed in two relatively telescopingly connected parts, and means to extend or to retract the outer part relative to the inner part, for projection or retraction of the thus-supported auxiliary body-supporting member.

5. A lounge chair as in claim 1, wherein the axis of the pivotal mount of the inner end of the arms upon the main body-supporting member is offset in a horizontal direction from the tilting axis of said main body-supporting member.

6. A lounge chair as in claim 5, wherein the axis of the arms' pivotal mount is offset to the rear of the tilting axis of the main body-supporting member.

FRANK J. LUKETA.
